United States Patent Office.

WILLIAM W. LOOMIS, OF WILKESBARRE, PENNSYLVANIA.

Letters Patent No. 95,699, dated October 12, 1869.

IMPROVED RAILWAY-BRAKE.

The Schedule referred to in these Letters Patent and making part of the same.

To all whom it may concern:

Be it known that I, WILLIAM W. LOOMIS, of the borough of Wilkesbarre, in the county of Luzerne, and State of Pennsylvania, have invented a certain novel and improved Method of Constructing and Applying Brakes to Railroad-Car Wheels; and I hereby declare the nature of my said invention, and in what manner the same is to be constructed and applied to one or more wheels of a railroad-car at the same time, by means of any of the many mechanical devices employed to operate car-brakes, as particularly described and set forth in and by the following statement, reference being had to the accompanying drawings, which are lettered to correspond with and form a part of the specification.

In order that the public may fully understand the nature of my invention, and those who are skilled in the mechanic art of railroad-car building, construct and apply the same, I will describe it as follows, to wit:

Plate 1 is a perspective drawing of a railroad-car, having my revolving brakes or wheels A A' applied to the hind wheels, 2 and 4, of the car. B B is an adjustable transverse bar, moving parallel to the axle-tree of the car, in the slots u u, by means of chains or wire rope c c c, operated by the brakeman, at K, at the front end of the car, and the wheels A A' revolve upon the transverse bar B B, and are carried out of contact with the car-wheels 2 and 4, by the action of the elastic springs s, secured in the slots or horizontal openings u u, in front of the adjustable bar or axes B B, to force the brakes A A' clear of the car-wheels, at the pleasure of the brakeman.

Plate 2 is a side elevation of a railroad-car, having a smaller brake-wheel, A", held down upon the rail R and in contact with the treading-periphery of the front wheel 1' of the car, by means of a stiff spiral or other suitable spring, s', operating the diagonal rod N, which is secured to the transverse axle-tree B of the brake-wheels A", at the lower end, and connected, at its upper end, to the chain which passes over the pulley P, and around the reel or base H of the brake-handle, which, in this instance, is employed to relieve or take the brake-wheel off the track R and out of contact with the car-wheel 1', by drawing the axle-tree B up the inclined groove or slot u', as shown at plate 3. Wheel or brake A" may be provided with a groove upon the outer periphery or bearing-surface, as shown at G, plate 4, so that an increased amount of friction

is produced upon the bearing or treading-surface of the wheel 1' of the car, when the brake A" is forced in contact with the same by the spiral or other spring s', when set free by the brakeman operating the handle K.

Plate 3 represents the revolving brake-wheel A" raised off of the rail R, and out of contact with the car-wheel 1'.

Plate 4 represents the treading-surface of the brake-wheel A", showing the groove G, which receives the flange of the car-wheel 1', if thought best to increase the friction and prevent the lateral sliding of the brake-wheels A" or A A'; yet, I believe a simple, plain-surfaced wheel, A, when properly arranged and applied as a brake for stopping a railroad-car, is the most effectual and surest means ever employed for such purposes.

Therefore, the novelty of my invention consists in the application and use of one or more revolving brake-wheels A, A', and A", mounted upon the adjustable axis B, so that the said brakes A, A', or A", may be brought in contact with the treading-surface of the car-wheels, (next the brakes,) by means as above set forth, or by any other device that will force the brake-wheels A, A', or A", in contact with the revolving car-wheels upon the track R, thereby reversing the action of either the brakes or the car-wheels themselves, which I believe to be equivalent, in effect upon the moving train, to reversing the engine.

Finally, I believe the whole arrangement of the above apparatus produces less wear upon the rails and wheels of the car, than any other brake ever employed for the purpose set forth. Therefore,

What I claim as novel and useful, and what I wish to secure by Letters Patent of the United States, is—

The revolving brake-wheels A, A', or A", at either or both ends of a railroad-car, mounted upon the adjustable axle-tree B, to operate upon the car-wheels 1', 2, by means of the slots u or u', suitable springs s s" wire ropes or chains c c c, or by any other suitable devices employed for working car-brakes.

In testimony whereof, I hereunto subscribe my name in the presence of two witnesses.

WILLIAM W. LOOMIS.
